CLAIM

The ornamental design for a tactically advanced combat mount illuminating system, as shown and described.

DESCRIPTION

FIG. 1 is a top, front, left side perspective view of a portion of the barrel of a long gun upon which has been installed the embodiment of the invention;

FIG. 2 is a front elevation view thereof, with each half of the embodiment being a mirror images of each other;

FIG. 3 is a right elevation view thereof, the left side being a mirror image; and,

FIG. 4 is an exploded top, front, left side perspective view thereof, the bottom, rear, right side perspective being a mirror image.

The gun barrel and flashlight are shown in broken lines in FIG. 1 for illustrative purposes only.
